Patented April 26, 1853.

Res. 555

Robert E. Deitz, of New York, N.Y.
Letters Patent No. 555 Dated 26th Apr. 1853,

The schedule referred to in these Letters Patent and making part of the same

To all whom it may concern:

Be it known that I, Robert Edwin Deitz, of the City, County, and State of New York, have invented or produced (a new design or figure to be cast in brass or other metal, which when finished are termed Girandoles, Candelabra, or ornaments,) and I do hereby declare that the following is a full & exact description of the same.

side holding an unfolding scroll, on which is the word "Hungary":-

Fig. 2, a cannon on which the right foot of the figure rests.

Fig. 3, a helmet.

Fig. 4, a sword.

Fig. 5, a fork.

Fig. 6, a battle-axe.

Fig. 7, a musket and bayonet.

Fig. 8, a war-club.

Figs. 9, 8, 10, flag and banner.

Fig. 11, a shield on a pedestal with the word "Li-ber-ty."

What I claim on my production and desire to secure by letters patent, is the combination and arrangement of the ornaments, as above described and set forth to form an ornamental Design for Girandoles, Candelabra, &c.
